his Attorney.

UNITED STATES PATENT OFFICE.

WILLIAM HENRY CLARKE-JAMES, OF LONDON, ENGLAND.

FASTENING AND LOCK FOR ATTACHE CASES AND THE LIKE.

Application filed November 11, 1922. Serial No. 600,371.

To all whom it may concern:

Be it known that I, WILLIAM HENRY CLARKE-JAMES, a subject of the King of Great Britain, residing at 32 Alfred Place, 5 Tottenham Court Road, London, England, have invented Improvements in and Relating to Fastenings and Locks for Attaché Cases and the like, of which the following is a specification.

10 This invention relates to fastenings and locks for attaché cases and the like. In the usual type of fastening and lock at present employed a spring controlled hasp having an eye on its under surface is engaged by a 15 spring controlled sliding catch or bolt which may be locked in its engaged position and such arrangement is found in practice to be unreliable since it is not possible to see whether the eye of the hasp is properly engaged in the locked position so that it often happens that when the case is being carried, the hasp suddenly flies out, the lid of the case opens and the contents of the case fall to the ground, now the primary objects of 20 25 the present invention are to overcome these defects and to produce a reliable and positive fastening and lock which visibly shows when the hasp is in a fastened or an unfastened position and in which it is rendered impossible for the hasp to become inadvertently unfastened or the fastening to be accidentally operated to release the hasp.

This invention will now be particularly described making reference to the accompanying drawing in which:

Fig. 1 is a view in front elevation of a lock embodying the present invention and showing the hasp in a fastened position.

Fig. 2 is a similar view showing the hasp 40 in an unfastened position.

Fig. 3 is a view in back elevation of the locking and fastening mechanism with the back casing removed.

Fig. 4 is a sectional view of the mechanism.

Fig. 5 is a broken view in back elevation of a modified form of lock.

Fig. 6 is a view in section of Fig. 5.

Fig. 7 is a view in back elevation of a further modification, with the back plate removed.

Fig. 8 is a view in section of the modification shown on Fig. 7.

Figs. 9, 10, 11 and 12 are broken views in front elevation of modified forms of fastenings, and

Fig. 13 is a view in section of Fig. 12.

Throughout the views similar parts are marked with like letters of reference.

On a plate *a* adapted to be secured to one part of the case is revolvably mounted a turn button. This button is provided either with an elliptical shaped head *b* as shown on Figs. 1, 2, 4, 9, 12 and 13 or with other suitably shaped head, for instance as shown on Figs. 10 and 11. The shank *b*¹ of the button is of a reduced diameter between its head and the surface of the plate *a*. On the other part of the case is fixed the usual hasp *c* which may be spring controlled which is furnished with an eye or opening *c*¹ corresponding in shape to the head *b* of the turn button and adapted to pass over the turn button and to be engaged by the head *b* on giving it a quarter turn as shown on Figs. 1, 9, 10, 11, 12 and 13.

The turn button may be so spring controlled that it always assumes either one or two definite positions and any suitable locking means operable by a key may be mounted on the back of the plate *a* so as to lock the turn button and prevent its rotation.

In the preferred construction of fastening and lock see Figs. 1-8, the turn button automatically assumes a fastened position on pressing the hasp *c* over it. In such constructions, see particularly Figs. 3 and 4, the shank *b*¹ of the button passes through the lock plate *a*, and the elliptical head *b* with finger operable wings *b*² thereon is fixed to the shank *b*¹ on the outer side of the lock plate *a*. On the shank *b*¹ on the inner side of the lock plate *a* is fixed a disc *b*³ in the periphery of which is a slot or notch *b*⁴. A spring pressed non-rotatable pin *d* projects through the lock plate *a* so that its projecting head will contact with and be pressed inwardly by the hasp *c* after passing over the head *b* of the turn button. This pin *d* is prevented from rotating by squaring its inner end adapting it to work in a square hole formed in a block *d*¹ carried on the housing

a^1 and is pressed outwardly by a spring d^2 . The pin d carries a tooth d^3 adapted to normally engage the slot or notch b^4 in the periphery of the disc b^3 but to be disengaged therefrom on pressing the pin d inwardly.

A spring—preferably a coiled spring e on a barrel b^5 on the shank b^1 or carried on the disc b^3 —is so arranged as to rotate the turn button in one direction as indicated by the arrow on Fig. 3. A pin or stop b^6 is carried by the disc b^3 to engage the tooth d^3 on the pin d so as to limit the movement of the disc to a quarter revolution—under the influence of the spring e —when the tooth d^3 is out of engagement with the slot or notch b^4 . In the periphery of the disc b^3 diametrically opposite the slot or notch b^4 , is a second slot or notch b^7 adapted to be engaged by the bolt f of usual lever locking mechanism f^1 when in correct position and the key of the lock is operated.

In the modification shown on Figs. 5 and 6, the turn button is rotated in an opposite direction (as indicated by the arrow on Fig. 5) to that of Figs. 3 and 4, by means of a helical tension spring e^1 and flexible connection e^2 fixed on the barrel b^5 . By such arrangement only one slot or notch b^4 in the disc b^3 is required as the bolt f of the locking mechanism can engage this slot after the button has turned a quarter revolution and been stopped in such position by the stop b^6 engaging the tooth d^3 of the pin d . The spring controlled pin d is prevented from rotating by allowing its tooth d^3 to engage a slot in the guide d^1 .

In the modification shown on Figs. 7 and 8, the key hole for the locking mechanism is situated centrally in the shank b^1 and locking mechanism is carried on the back of the disc b^3 formed in one with or carried by the shank b^1 . In this construction the disc b^3 tends to rotate in the direction of the arrow by means of a coil spring e .

The disc b^3 is held in its one position to allow the hasp passing over the head b by means of the tooth d^3 carried by the non-rotatable spring controlled pin d engaging the slot b^4 in the periphery of the disc b^3 .

When the pin d is pressed inwardly by the hasp, the tooth d^3 rides on the face of the turning disc until the one limb of the forked bolt f engages said tooth and so prevents further movement of the disc. The locking mechanism in this construction is of the simplest form, it comprises a slotted bolt f guided and controlled in its movement by fixed pins f^2 and having a projection f^3 adapted to be engaged by the key to move it.

The bolt is frictionally engaged by a spring pressed plate f^4 carried by the back plate f^5 . The plate f^4 also serves to keep the disc b^3 in proper position. When the hasp is fastened, the one limb of the forked bolt will be in engagement with the tooth d^3 ,

so that on shooting the bolt by a key, both limbs of the bolt will engage the tooth and so prevent relative movement of the parts.

In a further modification the usual form of lever lock may be employed with a centrally disposed key hole in the shank in which case the locking mechanism is carried on the non-movable back plate.

To prevent relative vertical movement of the two parts to which the plate a and hasp c is fixed when in the closed position in the constructions shown on Figs. 1 and 2, a pin c^2 is furnished on the under side of the hasp adapted to engage a hole a^3 in the plate a . It will be seen that such registering means is not required either in the constructions shown on Figs. 9-11 due to the shape and relative arrangement of the buttons and eyes in the hasps or in the modification shown on Figs. 12 and 13 in which the plate a is recessed and the hasp c is cranked to enter such recess.

I declare that what I claim and desire to secure by Letters Patent is:—

1. A fastening for attaché cases and the like comprising in combination a plate carried on the one part of the case, a turn button having an irregularly shaped head mounted to turn on said plate, a hasp carried on the other part of the case provided with an opening therein corresponding in shape to the head of the turn button and adapted to pass over it and to be engaged by the head on giving it a quarter turn, a notched disc fixed to the shank of the turn button, a spring tending to rotate said disc, a spring pressed non-rotatable pin carried on and having a head projecting through the plate and so positioned thereon as to be engaged by the hasp when the latter is in engagement with the turn button, a tooth carried on said pin and normally engaging the notched disc when the turn button carried therein is disengaged from the hasp but disengaging said disc on the hasp pressing the pin inwardly, and a stop carried on said disc adapted to engage the tooth on the pin when the disc has turned one quarter revolution under the influence of its spring, as set forth.

2. A fastening for attaché cases and the like comprising in combination a plate carried on the one part of the case, a turn button having an irregularly shaped head mounted to turn on said plate, a hasp carried on the other part of the case provided with an opening therein corresponding in shape to the head of the turn button and adapted to pass over it and to be engaged by the head on giving it a quarter turn, a notched disc fixed to the shank of the turn button, a spring tending to rotate said disc, a spring pressed non-rotatable pin carried on and having a head projecting through the plate and so positioned thereon as to be en-

gaged by the hasp when the latter is in engagement with the turn button, a tooth carried on said pin and normally engaging the notched disc when the turn button carried thereon is disengaged from the hasp but disengaging said disc on the hasp pressing the pin inwardly, a stop carried on said disc

adapted to engage the tooth on the pin when the disc has turned one quarter revolution under the influence of its spring and a key 10 operable sliding bolt adapted to lock the disc from rotation, as set forth.

WILLIAM HENRY CLARKE-JAMES.
